UNITED STATES PATENT OFFICE

FREDERICK G. HALLDEN, OF JAMAICA, NEW YORK, ASSIGNOR TO INTERNATIONAL COMMUNICATIONS LABORATORIES, INC., OF NEW YORK, N. Y., A CORPORATION OF NEW YORK

SINGLE LINE REPEATER

Application filed June 6, 1930. Serial No. 459,598.

This invention relates to telegraph systems and more particularly to improvements in devices for repeating or re-transmitting signals over connecting lines.

5 When sending and receiving stations are separated by considerable distances it is often desirable to overcome the retarding and weakening effects of transmitting signals over the connecting lines by introducing repeaters 10 at intermediate points along the line.

Among the types of repeaters heretofore used for this purpose are those employing two or more relays in which both line circuit and local circuit windings are provided. 15 Most of these systems depend for their successful operation upon an extremely delicate adjustment of the proper balance between the forces respectively exerted upon the relays by the signalling impulses and by the 20 locally controlled currents and speed of transmission is often sacrificed in order to insure against operating the repeaters falsely.

Accordingly it is the primary object of this invention to provide repeating equipment in which the operation of the relays will be more positively controlled by the local currents and in which such control shall persist during moments when the relay armatures are in transit from one contact to another. 25 A further object is to provide equivalent delays in the re-transmission of marking and spacing signals. It is obvious that the attainment of this latter object minimizes the distortion to which the re-transmitted 30 signals might otherwise be subjected. Further objects will appear in the detailed description hereinafter given.

The invention may be more fully understood from the following description, together with the accompanying drawing in which:

Figure 1 represents diagrammatically one embodiment of the invention.

45 Fig. 2 represents also diagrammatically, a slightly modified arrangement.

Referring to Fig. 1, two stations are shown interconnected by lines 1 and 2 through the repeater set R. The terminal 50 stations comprise sounders or other receiv-

ing instruments 3, and grounded transmitting keys or their equivalent 4.

Relays 5 and 6 in the repeater set have line circuit windings 7-8 and 9-10; also biasing coils 11-12 and 13-14. Two other 55 relays 15 and 16 have operating coils 17-18 and biasing coils 19-20. Line 1 is grounded at station A when key 4 is closed. If desired, a battery may be introduced between key 4 and ground. 60

This circuit includes station A, sounder 3 and winding 7-8 in the repeater relay 5 and connects through spacing contact and armature of relay 16 with the resistance 21 and grounded battery 22. Line 2 is grounded (optionally through a battery) at station B through key 4 and connects station B, sounder 3 with coil 9-10 in the repeater relay 6. This circuit also includes the spacing contact and armature of relay 15 and thence it is connected through the resistance 23 with the grounded battery 24. Various resistances and inductances are provided in connection with the other relay circuits as will be explained in describing the 75 operation of the relays.

Referring to the modified arrangement shown in Fig. 2 it will be observed that the details at the terminal stations A and B are exactly the same as shown in Fig. 1. The 80 line circuits pass through relay windings 7-8 and 9-10 respectively as heretofore described. Non-polarized relay 32 (which is alternative to relay 15) is arranged with its coils 34-35 in series; and so, likewise in 85 regard to non-polarized relay 33 (which is alternative to relay 16). No biasing circuit is needed for these relays because their armatures are normally held against the marking contacts by springs 36. Other 90 modifications will presently be set forth.

The operation of the repeater shown in Fig. 1 is as follows: If the operator at station A transmits signals over line 1 by opening and closing his key 4, then the current 95 through coil 7-8 of relay 5 will be interrupted. With the key 4 closed the direction of current is represented as from station A through line 1 to coil terminal 7, thence to coil terminal 8, spacing contact 100

and armature 28 of relay 16, and through resistance 21 to negative battery 22. The ampere turns in coil 7-8 may be adjusted to approximately twice the number of ampere turns set up in the opposite direction through the biasing coil 12-11. Armature 25 will then be held against the marking contact when key 4 is closed, and against the spacing contact when key 4 is opened 10 and in the latter case the biasing coil 12-11 acts alone. Current is fed to coil terminal 12 through a resistance *a* from the grounded battery 31. After passing through the coil to terminal 11 this biasing circuit includes 15 an inductance 37, the marking contact and armature 26 of relay 6, and finally a grounded resistance 38.

When coil 12-11 acts alone, the armature 25 is thrown against its spacing contact, thus closing a circuit from grounded battery 39 through a resistance 40, coil 17-18 and thence to spacing contact and armature 25 of relay 5. This armature is grounded through the resistance 41. The ampere turns in coil 17-18 will be fixed at approximately twice the opposing ampere turns through the biasing coil 20-19, the latter being in a closed circuit which includes the battery 42 and resistance 43. Hence the shifting of armature 25 to the spacing contact of relay 5 results in shifting armature 27 to marking contact of relay 15, which opens the line circuit 2 and de-energizes the sounder 3 at station B. The circuit through line 2 may be traced (assuming it to have been normally closed) from grounded key 4 at station B, through the sounder 3, line to repeater set R, relay winding 9-10, spacing contact and armature 27 of relay 15 and thence to resistance 23 and grounded battery 24. To hold this circuit open while at the same time both lines 1 and 2 are kept under the control of the operator at station A, it is necessary that 45 relays 6 and 16 should not at this time be actuated. This is accomplished as follows:

When line 2 is a closed circuit, the ampere turns developed in coil 9-10 of relay 6 will exert a force to hold armature 26 against the marking contact of relay 6. The opposing ampere turns of the biasing coil 14-13 are normally adjusted to approximately one-half the force exerted by coil 9-10. But when relay 5 operates to throw its armature 25 against the spacing contact, the current in the biasing coil 13-14 is reversed. This is brought about by the proper choice of battery potentials and resistances so that when armature 25 is against the marking contact current will flow from battery 31 through resistance *c* and through the biasing coil 14-13 of relay 6, thence through the inductance coil 44 to marking contact and armature 25 of relay 5, being grounded through a comparatively low resistance 41. When,

however, this circuit is opened by throwing armature 25 against the spacing contact, then current is fed from battery through the comparatively high resistance 46 in the reverse direction through retard coil 44 and biasing coil 13-14, thence through resistance *d* to ground. This change in the direction of current in the biasing coil 13-14 takes place immediately upon separation of armature 25 from its marking contact and hence the energizing force in coil 13-14 builds up to hold armature 26 against the marking contact before the current in coil 9-10 is dropped to zero by being cut off at relay 15 spacing contact and armature 27. 75

It will be understood, therefore, that when the transmission of signals originates at station A, relay 6 will not be operated and as long as this relay remains inactive, relay 16 will also remain inactive, thus keeping a closed path for line 1 through the spacing contact and armature 28 of relay 16, for obviously if the circuit were to be opened at this point then the operator at station A would lose his source of potential 22 and not be able to control the repeater by again closing his key 4. 80

When the key 4 at station A is again closed, the circuit through line 1 to ground causes relay armature 25 to move to its marking contact. The circuit through coil 17-18 of relay 15 is thus broken leaving the biasing coil 20-19 to act without opposition in throwing armature 27 against its spacing contact, whereat the circuit in line 2 is again established. The biasing current through coil 14-13 is again reversed but not until armature 25 has reached its marking contact and after further delay in passing through the inductance coil 44; whereas the current in coil 10-9 was more rapidly built up from the instant that armature 27 reached the spacing contact of relay 15; its excursion being practically simultaneous with that of armature 25 on relay 5. 100

It is obvious from the symmetrical arrangement of the repeater relays and their connections, that transmission may be initiated with equal facility either at station A or at station B. If station B transmits, then relays 6 and 16 would operate precisely the same as has been described with respect to relays 5 and 15 while the latter would then remain idle. 110

The operation of the modified arrangement shown in Fig. 2 will now be explained. The armature 25 of relay 5 is normally held against its marking contact while current flows from grounded key 4 at station A through line 1, coil 7-8, marking contact and armature 30 of non-polarized relay 33, resistance 21 and thence to grounded battery 22. When the operator at station A opens his key 4, the coil 7-8 becomes de-energized and as its ampere turns are adjusted to exert ap- 120 125 130

proximately twice the force oppositely maintained in the biasing coil 12-11, the relay 5 is now actuated by the latter coil, current flowing through it from battery 31 and resistance α . This circuit is then conducted to armature 26 and marking contact of relay 6, thence through a resistance 47 and inductance coil 48 to ground.

While armature 25 of relay 5 is in transit from its marking to spacing contact, the current flow from battery 31 through the biasing coil 13-14 of relay 6 is reversed by impressing upon the circuit at the point 51 a positive potential from battery 52 through the comparatively high resistance 53. Thus the relay 6 is caused to anticipate the loss of its holding current through coil 10-9 and at no time is there any tendency for its armature to leave the marking contact while transmission proceeds from station A.

The movement of armature 25 against the spacing contact of relay 5 causes a circuit to be completed through the coil 34-35 of the non-polarized relay 32, starting from grounded battery 39 and after passing through relay 32 to armature 25 is conducted to coil 13-14 of relay 6 and thence through resistance d to ground. This current is in opposition to that proceeding from battery 31 and is adjusted to overpower the latter in order to retain armature 26 against its marking contact while current ceases to flow in coil 9-10 of relay 6, this being the result of actuating relay 32 to open the circuit for line 2 at the parting of armature 29 from its marking contact.

The relay 32 is actuated against the tension of a spring 36 which tends to hold armature 29 against its marking contact. It will thus be seen that when key 4 is again closed at station A, and relay armature 25 of relay 5 moves away from its spacing contact, the breaking of the circuit through coil 34-35 will allow the spring 36 to restore armature 29 to marking contact, thereby re-establishing the closed circuit condition for line 2 from battery 24, the same as was described in reference to Fig. 1.

Just as there is a delay in transferring a spacing signal from line 1 to line 2 due to the fact that armature 29 is not pulled away from its marking contact until armature 25 reaches its spacing contact, so also, a marking signal in line 1 is transferred to line 2 with such delay as is incidental to the travel time of armature 29 from spacing to marking contacts. The distortion of signals is therefore, practically negligible. As soon as armature 25 leaves its spacing contact, coil 34-35 commences to de-energize. Hence the biasing spring 36 in relay 32 begins to actuate the armature 29 while armature 25 is in transit. The two armatures reach their marking contacts almost simultaneously and therefore the signalling impulse in line 2

builds up through coil 9-10 of relay 6 in opposition to the biasing current through coil 13-14 from battery 31. Since, however, this latter force is retarded by the inductance 50, there is no tendency for the current reversal in coil 13-14 to actuate the armature 26 and hence both relays 6 and 32 remain inactive during transmission from station A.

Transmission from station B will be easily understood from the symmetrical arrangement of the repeater.

What is claimed is:

1. A telegraph repeater comprising two sets of relays, at least one relay of each set having a plural winding, a line connection with one of said plural windings in one set, another line connection with a corresponding winding in the other set, a connection between the line connected winding of each set and a relay contact of the opposite set, a connection between a relay contact of each set and a winding of another relay in the same set, a biasing circuit in each set reversibly controlled by the actuation of a relay in the opposite set, and a local source of energy for actuating the relays of said repeater in response to line transmitted signals.

2. The invention set forth in claim 1 in which the relays of one set are prevented from responding to the signals to which the other set responds.

3. The invention set forth in claim 1 in which the relays of one set are rendered inactive by a reversal of current flow in one of the windings anticipatory to a cessation of current flow in another winding of the same relay.

4. The invention set forth in claim 1 in which the relays of one set are rendered inactive by delaying a reversal of current in one of the windings until after the current flow in another winding of the same relay has commenced to build up.

5. A telegraph repeater comprising a set of relays responsive to incoming signals from one loop circuit, another set of similar relays responsive to incoming signals from a second loop circuit, there being only one relay winding in each loop circuit and biasing windings in said relays, potential for energizing said windings and said loop circuits, means for re-transmitting the signals to which one set of relays is caused to respond to the loop circuit which includes the other set of relays, and bias-reversal means to render said latter set of relays inactive during said re-transmitting of signals therethrough.

6. The invention set forth in claim 5 in which the bias-reversal means are respectively caused to anticipate or to lag behind the re-transmitted signals according as the potential of the latter is being reduced or built up.

7. A telegraph repeater comprising a line relay responsive to input signals, another line

- relay irresponsible to output signals conducted therethrough, supplementary windings in said line relays, an auxiliary relay associated with each said line relay and operated there-
 5 by, means for reversing the current flow in the supplementary winding of the irresponsible line relay anticipatory to an interruption of current flow representing an output signal caused by the actuation of one of said auxiliary relays.
8. A telegraph repeater comprising a line relay responsive to input signals, another line relay irresponsible to output signals conducted therethrough, supplementary wind-
 15 ings in said line relays, an auxiliary relay associated with each said line relay, means for causing one of said auxiliary relays to re-transmit a signal anticipatory to a reversal of current flow in the supplementary winding of the irresponsible line relay.
9. A telegraph repeater comprising a line relay responsive to input signals, another line relay irresponsible to output signals conducted through a winding thereof, an auxiliary
 25 relay associated with each said line relay, means to actuate one of said auxiliary relays from the responsive line relay to re-transmit through the irresponsible line relay, and bias reversal means to lock the last said relay in
 30 advance of a re-transmitting circuit interruption and to unlock the same in arrears of a re-transmitted impulse.
10. A telegraph repeater comprising a line relay responsive to input signals and irre-
 35 sponsive to output signals transmitted over a given line circuit, a re-transmitting relay operable from said line relay, a second line relay and a second re-transmitting relay operable therefrom in response to input signals
 40 transmitted over a second line circuit and likewise irresponsible to output signals re-transmitted over said second line circuit, current sources for said relays and for said line circuits, an armature marking and spacing
 45 contact device for each relay, main windings and auxiliary windings for each relay with biasing means whereby potential is duly applied from the current sources to the auxiliary windings of the line relay in opposi-
 50 tion to the force of the input signals and in sustentation of the interrupted force of the output signals.
11. A telegraph repeater comprising a polar line relay for each of two loop circuits,
 55 and a re-transmitting relay associated with each line relay, there being only one relay winding included in each loop circuit.
12. A telegraph repeater comprising a pair of polar line relays responsive to input sig-
 60 nals and irresponsible to output signals, a re-transmitting relay responsive to the operation of said responsive line relay for repeating signals through the other line relay, current reversing means controlled by the responsive line relay for preventing the op-
 65 eration of the other line relay and means controlled by said other line relay for preventing the operation of a retransmitting relay associated therewith.
13. A telegraph repeater comprising a pair of polar line relays responsive to input signals and irresponsible to output signals, signalling means for operating one of said line relays, a retransmitting relay responsive to the operation of said operated line relay for repeating signals through the other line relay, and means controlled by the responsive line relay for reversing the current in only one winding, said winding being the biasing winding of the other line relay.
14. A telegraph repeater comprising a pair of polar line relays responsive to input and irresponsible to output signals, a retransmitting relay responsive to the operation of one of said line relays for repeating signals through the other line relay, and means for reversing the current in only one winding, said winding being the biasing winding of the other line relay, when the operated line relay armature begins movement in one direction, and for again reversing the current in said winding when said armature ends its movement in the other direction.
15. A telegraph repeater comprising a line relay responsive to input signals, another line relay irresponsible to output signals conducted through a winding thereof, an auxiliary relay controlled by each of said line relays, means for actuating one of said auxiliary relays from the responsive line relay to re-transmit through the irresponsible line relay, and current reversing means for locking the irresponsible line relay in advance of a retransmitting circuit interruption and for unlocking said relay in arrears of a retransmitting circuit closure.
16. A telegraph repeater comprising a line relay responsive to input signals, another line relay irresponsible to output signals, an auxiliary relay associated with each of said line relays, means for actuating one of said auxiliary relays from the responsive line relay to re-transmit through the irresponsible line relay, and current reversing means for locking the irresponsible line relay in advance of the operation of said auxiliary relay in one direction and for unlocking said relay in arrears of its operation in the other direction.
17. A telegraph repeater comprising two sets of relays in which the relays of one set are rendered inactive by delaying a reversal of current in a winding of a relay of the said set by means of an impedance in the circuit of the said winding until after the current in another winding of the same relay has commenced to build up.
18. A telegraph repeater comprising two sets of relays in which the relays of one set are rendered inactive by a reversal of current flow in a winding of but one relay of the

said set anticipatory to a cessation of current flow in another winding of the same relay.

19. A telegraph repeater comprising two sets of relays in which the relays of one set are rendered inactive by reversing the current in a winding of but one relay of the said set and causing the current in said winding to build up more slowly than the current in another winding of the same relay.

20. In witness whereof, I hereunto subscribe my name this 4th day of June, 1930.
